DOOR STOP CONSTRUCTION

Viles K. Fremstad, Van Nuys, Calif., assignor to Ajax Hardware Manufacturing Corporation, Los Angeles, Calif., a corporation of California

Application January 10, 1955, Serial No. 482,320

4 Claims. (Cl. 16—85)

The present invention relates generally to builders' hardware, and more particularly to door stops having flexible shanks.

Door stops of this character are designed to be attached to the base of a vertical wall in order to receive the impact from the door swinging back against the wall and thus protect the wall, as well as the door, from damage. Door stops for this purpose having a rigid shank have been well known for a long time. However, they have suffered from the great disadvantage that the rigid stop did not yield when struck from the side. When a vacuum sweeper or a mop or other cleaning instrument hit the door stop with sufficient force, either the shank was broken or the door stop as a whole was torn off from the face of the wall. Repeated injury to or loss of door stops from this cause has frequently resulted in failure to replace them with the consequent loss of the protection that they afford.

In order to remedy this situation, door stops with flexible shanks have been devised. These are designed to yield under laterally applied blows and then return to their normal position. Known designs of flexible door stops succeed in this objective only to a certain extent, because when the blow is applied close to the base of the door stop, the flexible shank is bent so sharply that it takes a permanent set and fails to return to its normal position. Once the door stop has been deformed sufficiently to no longer return to its normal position, it is often as useless as if it had been broken or torn off the wall.

Hence it is a general object of my invention to provide an improved design for a door stop having a flexible shank which will insure that it yields to all lateral blows and then will return to its normal position.

It is also an object of my invention to provide an improved design for a door stop with a flexible shank in which the shank is so designed that it will deflect sharply in the vicinity of its base without taking a permanent set.

These objects of my invention have been achieved in a door stop comprising a flexible shank of novel design having an impact receiving head attached to one end of the shank and a base attached to the other end by which the door stop is mounted on a wall or other supporting means. The shank is in the form of a coil spring having a plurality of successive turns, which, for at least the major portion of the shank, are in engagement with each other. The turns of the coil are not of uniform diameter throughout the entire length of shank. Rather, the shank is formed with a section intermediate its ends at which the turns are of maximum diameter. The diameter of the turns decreases progressively in either direction away from this point of maximum diameter and toward the ends of the shank.

In a preferred construction, the first several turns at one end of the shank are of uniform diameter and engage the base by which the door stop is mounted on its support. Adjoining this section is a section in which the

turns increase progressively in diameter away from the base. This may be followed by another section in which the turns of the successive coils decrease in diameter outwardly of the shank.

5 How the above objects and advantages of my invention, as well as others not specifically mentioned herein, are attained will be better understood by reference to the following description and to the annexed drawing, in which:

10 Fig. 1 is a perspective view of a door stop constructed according to my invention, showing the door stop in operating position;

15 Fig. 2 is a side elevation of the door stop showing how it bends in response to a blow applied laterally at the outer end;

Fig. 3 is a similar view on an enlarged scale, partially in vertical median section, showing how the door stop deflects in response to a force applied laterally near the base;

20 Fig. 4 is a vertical transverse section on line 4—4 of Fig. 3; and

Fig. 5 is a side elevation of a variational form of door stop.

25 Referring now to the drawing, it will be seen that the door stop comprises three principal portions, a flexible shank 10, a mounting base 11 at one end of the shank, and a blow receiving head 12 on the other end of the shank. Base 10 is of well known construction and includes a wood screw 14 which may be screwed into a wall or the like in order to mount the door stop in the proper position. The mounting base is also provided with a section 15 having a plurality of flat sides which may be gripped by a wrench for the purpose of turning the base in order to advance screw 14 into the support.

30 Shank 10 is a coil spring which preferably has its successive turns in contact with each other, for at least a major portion of its length, in order to give desirable rigidity to the shank to resist endwise blows. Being a spring, it yields, as shown in Fig. 2, to laterally directed blows applied at or near the outer end, as represented by arrow 16.

35 At the inner or base end, the shank has an initial section 10a comprising a plurality of turns of uniform diameter. These surround a short threaded stud 18 which is part of base 11 in order to attach the base to the shank. Other means of connecting the shank and base together may be used if desired.

40 Adjoining shank section 10a but outwardly therefrom is section 10b of the shank. In this section the diameter of the several turns increases progressively outwardly from base 11. The rate of increase is such that the turns still keep contact with each other, each turn being larger than the preceding one by preferably about one-half the diameter of the wire from which the spring is wound. 45 This prevents the turns from telescoping when endwise blows are applied to the shank.

45 The largest diameter of the coils may be continued on as shown in Fig. 5, if desired, to the outer end of the shank; but it is preferred to reduce the diameter gradually 50 to about the initial diameter. Hence section 10b adjoins a section 10c, longer than the others, in which the diameter of the several turns gradually decreases, outwardly of the shank, from the maximum value.

55 At the extreme outer end, where head 12 is mounted on the shank, the diameter is conveniently the same as at the base end. This shank design offers a pleasing appearance with its largest diameter at a position intermediate the ends of the shank and gradually tapering in size toward each end.

70 As a consequence of this construction, the shank deflects under lateral loads when applied near the base, as

represented by the arrow 20 in Fig. 2, without taking a permanent set. When the load is applied near the end of stud 18, all the deformation must occur in the shank between the end of the stud and the point of application of the force. Hence most of the deformation takes place in the short length of section 10b. This section can undergo considerable deformation without permanent change of shape. It appears that the successive turns, because of the progressive change in diameter, are able to slide laterally over one another at the side away from the force and to spread apart on the near side in a manner to give a sharp bend to the shank as a whole but without concentrating the bending in any one turn to such a degree as to give it a permanent set. The progressive change in diameter of the turns allows them to move more relative to each other than if they were all the same size. As a consequence, a shank of my novel design returns to its normal position repeatedly after blows that can permanently bend a spring of uniform diameter.

A variational form of door stop is shown in Fig. 5 which is the same as that already described except that the diameter of the turns does not decrease in section 10c, the maximum diameter of section 10b being continued on to the outer end of the shank. When the shank deflects under lateral loads, deformation takes place in section 10b as described above.

Since various changes can be made in the design of my novel door stop without departing from the spirit and scope of my invention, it is to be understood that the foregoing description is considered to be illustrative of, rather than limitative upon, the scope of the appended claims.

I claim:

1. A door stop comprising a helical spring member forming a shank one end of which is provided with a base

member having an outwardly projecting stud portion to which the said end of the shank is secured by engagement of the coils therewith, the opposite end of said shank having an impact receiving head attached thereto, said shank being provided intermediate its ends with a portion of increased diameter lying adjacent to but spaced from the outer end of the stud portion of the base member.

5 2. A door stop as claimed in claim 1, wherein the end of said shank having an impact receiving head attached thereto is of a diameter generally approximating that of the end thereof engaging said stud portion.

10 3. A door stop as claimed in claim 1, wherein the portion of said shank of increased diameter has its coil portion of greatest diameter located adjacent to the outer end of the stud portion but spaced therefrom, the said portion of increased diameter tapering toward the stud-engaging end portion of the shank.

15 4. A door stop as claimed in claim 1, wherein the portion of said shank of increased diameter has its portion of greatest diameter located adjacent to the outer end of the stud portion but spaced therefrom, the said portion of increased diameter tapering toward both ends of the shank.
